UNITED STATES PATENT OFFICE.

GUY C. HENKLE, OF CHICAGO, ILLINOIS.

CONCRETE-BLOCK MOLD.

1,242,439.

Specification of Letters Patent.

Patented Oct. 9, 1917.

Application filed June 3, 1916. Serial No. 101,538.

To all whom it may concern:

Be it known that I, GUY C. HENKLE, a citizen of the United States, and resident of Chicago, in the county of Cook and State of Illinois, have invented certain new and useful Improvements in Concrete-Block Molds, of which the following is a specification.

The present invention relates to new and useful improvements in the art of plastic block and earthenware apparatus and has particular reference to improvements in block molds.

The primary object of my invention is to provide a device of the class described which may be employed for forming a plurality of concrete blocks or the like simultaneously, the mold being of the knock-down type facilitating removal of the articles formed therein after hardening.

Another object of my invention is to provide a mold of the class described which will permit the formation of building block and the like with either curved or straight surfaces, the construction of the mold permitting formation of a block of any curvature within certain limits.

A further object of my invention is to provide a mold of the class described, simple in construction, strong and durable and capable of a wide range of adjustment for producing various sizes of blocks or the like.

Other objects and advantages to be derived from the use of my improved mold will appear from the following detail description and the claims, taken with an inspection of the accompanying drawings, in which:

Figure 1 is a perspective view of a block mold embodying the improvements of my invention;

Fig. 2 is a vertical transverse sectional view of the same;

Fig. 3 is a vertical longitudinal sectional view of the same;

Fig. 4 is a horizontal longitudinal sectional view taken on the line 4—4 of Fig. 3 looking in the direction of the arrow;

Fig. 5 is a modified form of partition which I employ when forming curved objects;

Fig. 6 is an enlarged fragmental sectional view showing the manner of hinging the sides of the mold; and

Fig. 7 is a sectional view of a crank member for use in connection with the mold.

Referring more particularly to the draw-

ings, wherein similar characters of reference designate like and corresponding parts throughout the various views, 1 and 2 designate the end frames of my improved mold, 60 said end frames being rectangular in configuration and preferably formed of angle-irons. The end frames 1 and 2 serve to support the body of the mold by means of a plurality of longitudinally arranged parallel spaced angle-irons 3, bolts 4 having threaded engagement as at 5 with said angle-irons extending through the upper portions of the end frames 1 and 2 and having polygonal heads 6 thereon for a purpose 70 which will hereinafter appear. Any number of the angle-irons and bolts may be provided, five being shown in the drawing.

The angle-irons serve to support a base 7 formed of sheet metal, in the present instance. Of course, the base 7 may be formed of wood, if desired, however, the metal base is provided because of the resiliency of the same permitting curvature of the mold when forming curved blocks and the like.

It will be seen from an inspection of Figs. 1 and 3 that the bolts 4 extend through the base plate 7 thereby serving to retain the same in position. The plate 7 has been broken away in Fig. 4 to permit the angle-irons to appear.

The sides of my improved mold are designated 8 and 9, said sides being provided with a plurality of vertically arranged recesses 10 and 11, respectively, said recesses 90 being relatively in alignment to receive a plurality of partitions 12 and end walls 13 and 14. A plurality of tongues 15 and 16 carried by the side walls 8 and 9 engage the end portions of the end frames to retain the 95 sides 8 and 9 against accidental displacement. The sides 8 and 9 are movably connected with the outermost of the angle-irons 3 by means of a plurality of bolts 17 having hook portions 18 on their lower free ends, 100 said hook portions extending through suitable apertures formed in the outermost angle-iron. Wing nuts 19 are carried by the upper extremities of the bolts 17 for clamping the sides when moved to a desired position.

When reinforcing the object molded it is essential that the reinforcing element be suspended within the chambers between the partitions at the proper point and for this 110 purpose I have provided blocks 20 provided with recesses 21, said blocks being arranged

on the sides 8 and 9 and being adapted to receive the free ends of the reinforcing element. Various sizes and shapes of blocks may be provided if desired.

- 5 When using my improved mold for forming curved objects I provide partitions similar to the partitions 12 hereinbefore described with the exception that these partitions are curved, one of the same being 10 best shown in Fig. 5 and designated 23. The partition 23 is provided on one face thereof with a flange 24, this for the purpose of forming a recess in the block or object molded.
- 15 Of course, when the curved partitions are employed the bottom of the device must also be curved. To curve the bottom plate 7 the outermost of the bolts 4 are tightened drawing the outermost angle-irons into position 20 out of alinement with the innermost angle-irons thereby curving the bottom 7 into conformity with the curvature of the partitions 23, of which there are a plurality forming both the intermediate partitions and the 25 end walls. In order to swing the sides 8 and 9 inwardly, the wing nuts 19 are disengaged from the bolts 17 which are then moved vertically. When these bolts are in this position it will be apparent that the sides may 30 be moved laterally owing to the slots 17' in the angle irons through which the bolts 17 extend. The wrench 25 having a handle 26 and a socket 27 is employed for operating the bolts 4. The flexibility of the bottom plate 7 permits the wide range of adjustment necessary in a device of this character, it being unnecessary to remove the base each 35 time and substitute the same with a different size base.
- 40 My invention may be cheaply constructed all of the parts being formed from stock material which may be obtained at small cost. Of course it will be understood that by substituting the transverse divisional partitions 45 of my improved mold with longitudinal partitions the mold may be adapted for use as a fence post mold.

From the above description taken in connection with the accompanying drawing, it 50 is thought that a clear and comprehensive understanding of the construction, operation and advantages of my invention may be had,

and while I have shown and described my invention as embodying a specific structure, I desire that it be understood that such changes may be made in said structure as do not depart from the spirit and scope of the invention as claimed.

Having thus fully described my invention, what I claim as new and desire to secure by Letters Patent, is:

1. A mold comprising end frames, a plurality of longitudinal parallel members engaging the end frames, a flexible bottom secured to the longitudinal members, means for flexing the same, partitions extending transversely across said bottom, angularly movable sides mounted at the edges of the bottom, and means for retaining the sides in various angular positions. 70

2. A mold of the class described, including a body formed with end frames, a base plate, supporting elements carried by said end frames to engage said plate, side members movably mounted on certain of said supporting elements, and means for clamping associating the side members with the supporting elements on which they are mounted. 75

3. A mold comprising end frames, a plurality of longitudinal parallel members engaging the same, a flexible bottom arranged on the longitudinal members, means for flexing the same, angularly movable sides mounted at the edges of the bottom, a plurality of longitudinally curved partitions extending transversely across the bottom, and means for retaining the sides in such angular position. 80 85

4. A mold comprising end frames, a plurality of longitudinal parallel members engaging the same, a flexible bottom mounted on the parallel members, adjusting bolts extending through the end frames for flexing the bottom, sides arranged at the opposite 90 edges of the bottom and capable of being moved to angular positions, a plurality of longitudinally curved partitions extending transversely across the bottom, and means for retaining the sides in such angular positions. 95 100

In testimony whereof, I affix my signature hereto.

GUY C. HENKLE.
